(57) **CLAIM**

The ornamental design for a controller for a handpiece for removing dead skin cells, as shown and described.

DESCRIPTION

FIG. 1 is a top, front and right side perspective view of the design;

FIG. 2 is a front elevational view thereof;

FIG. 3 is a back elevational view thereof;

FIG. 4 is a left side elevational view thereof;

FIG. 5 is a right side elevational view thereof;

FIG. 6 is a top plan view thereof;

FIG. 7 is a bottom plan view thereof; and,

FIG. 8 is another top, front and right side perspective view, shown in an environment.

In FIGS. 3, 6 and 7, the broken lines are for the purpose of illustrating portions of the controller for handpiece for removing dead skin cells that form no part of the claimed design. In FIG. 8 the broken lines are for the purpose of illustrating environment only that form no part of the claimed design.
